PACKAGING PAD OR THE LIKE

James W. Boyd, Crown Point, Ind., assignor to Packaging Corporation of America, Evanston, Ill.

Filed Sept. 20, 1971, Ser. No. 182,313

Term of patent 14 years

Int. Cl. D9—99

U.S. Cl. D9—294

FIG. 1

FIG. 2

FIG. 3

FIG. 4

FIG. 5

FIG. 6

FIG. 7

FIG. 1 is a top plan view of a packaging pad or the like embodying my new design.

FIG. 2 is an enlarged fragmentary view partially in section and taken along line 2—2 of FIG. 1.

FIGS. 3—7 are enlarged sectional views taken, respectively, along lines 3—3, 4—4, 5—5, 6—6, and 7—7 of FIG. 1.

I claim:

The ornamental design for a packaging pad or the like, substantially as shown.
